UNITED STATES PATENT OFFICE.

DANIEL J. CLUPKA, OF GAINESVILLE, FLORIDA.

WEIGHING-SCOOP.

956,626.

Specification of Letters Patent.

Patented May 3, 1910.

Application filed June 15, 1909. Serial No. 502,341.

To all whom it may concern:

Be it known that I, DANIEL J. CLUPKA, a citizen of the United States, residing at Gainesville, in the county of Alachua and

5 State of Florida, have invented new and useful Improvements in Weighing-Scoops, of which the following is a specification.

This invention relates to weighing scoops, the object in view being to provide a simple 10 and practical device of the class described by means of which the contents of the scoop may be accurately weighed without interfering with the use of the scoop as such.

With the above and other objects in view, 15 the nature of which will more fully appear as the description proceeds, the invention consists in the novel construction, combination and arrangement of parts as herein fully described, illustrated and claimed.

20 In the accompanying drawings:—Figure 1 is a longitudinal section through a weighing scoop embodying the present invention. Fig. 2 is an enlarged cross section on the line 2—2 of Fig. 1. Fig. 3 is a similar view 25 on the line 3—3 of Fig. 1.

Referring to the drawings, 1 designates the body of the scoop which may be of any desired size and capacity and the shape of which is immaterial.

30 In carrying out the present invention, the body of the scoop is provided with a stem 2, which is mounted to move within a hollow or tubular handle comprising an outer shell or casing 3 and an inner core or body 4.

35 This core or body 4 is provided with a longitudinal bore 5 in which the stem 2 is adapted to slide, a weighing spring 6 being arranged behind the stem 2 and interposed between said stem and the outer extremity of

40 the handle which is closed and recessed as shown at 7 to form a pocket in which one end of the spring 6 is seated and held. The opposite end of the spring may, if desired, encircle the adjacent end of the stem 2 and 45 be connected thereto in any convenient manner.

The stem 2 is provided at diametrically opposite points with longitudinal ribs 8 and 9 while the core 4 is correspondingly grooved 50 to receive said ribs, the result being that relative movement is prevented between the stem and handle which adds much to the practical value of the scoop as it prevents

the scoop from turning over while it is being manipulated for the purpose of scooping 55 up produce from a bin.

One of the ribs 9 is provided with a rack face 10 and coöperating with said rack face is a catch lever 11 provided with a single tooth 12 adapted to engage the rack face of 60 the rib 9. The catch lever is fulcrumed at an intermediate point as shown at 13 between a pair of lugs 14 arranged in a recess 15 in the core 4 as best illustrated in Fig. 2. One arm of the catch lever 13 has associated 65 therewith the stem 16 of a push button 17 which works through an opening in the outer shell or casing 3 and is normally held outward by means of a spring 18 interposed between the head of the button and the outer 70 wall or shell 3. A pin or key 19 limits the outward movement of the button and prevents the stem 16 from escaping. An additional spring 20 is arranged under the projecting arm of the catch lever and acts to 75 normally hold the tooth 12 in engagement with the rack face 10 of the rib 9. The material is scooped from a bin or receptacle in the ordinary manner and is then held with the scoop body 1 uppermost thereby bringing the weight of the material on the weighing spring 6. The button 17 is 80 then pressed inward which allows the stem 2 to slide within the handle. The stem 2 may then be locked and held at such point 85 by means of the catch lever allowing more material to be introduced in the scoop or some of the material to be removed therefrom until the exact amount of material is contained in the scoop. The catch lever 11 90 holds the scoop body in rigid relation to the handle while dipping the scoop into the material to be weighed thereby adding to the practical utility and value of the device.

The stem 2 is graduated or marked off in 95 a scale as indicated at 21, the said scale, used in connection with a pointer or fixed marking or indicating device on the handle showing when the proper weight of material is contained in the body of the scale. 100

I claim:—

A weighing scale comprising a scoop body, a graduated stem projecting therefrom, a handle in which the stem slides, said handle being provided with a groove, a weighing 105 spring in the handle on which the stem

rests, a rack faced longitudinal rib on the stem working in the groove in the handle, and a thumb operated spring catch mounted in the handle and adapted to be moved into 5 and out of engagement with the rack faced rib to hold the stem against movement in the handle.

In testimony whereof I affix my signature in presence of two witnesses.

DANIEL J. CLUPKA.
